W. WEBSTER.
FIRE DAMPER REGULATOR.

No. 36,252.

Patented Aug. 19, 1862.

UNITED STATES PATENT OFFICE.

WILLIAM WEBSTER, OF MORRISANIA, NEW YORK.

FIRE-DAMPER REGULATOR.

Specification of Letters Patent No. 36,252, dated August 19, 1862.

To all whom it may concern:

Be it known that I, WILLIAM WEBSTER, of Morrisania, in the county of Westchester, in the State of New York, have invented a new and useful Improvement in Fire and Damper Regulators; and I do hereby declare that the following is a full and exact description thereof, reference being had to the accompanying drawing, in which—

10 Figure 1 is a vertical section of and Fig. 2 is a top view of my improved regulator.

The nature of my improvement consists in the construction of fire and damper regulators in which a metallic piston moves in 15 a metallic cylinder, a cylindrical piece of vulcanized india rubber, or other vulcanized material, being inclosed and securely held in position between the piston and the cylinder, the vulcanized india rubber serving, 20 as thus employed, the purpose of offering an elastic resistance to the motion of the piston.

To enable others skilled in the art to make and use my improvement, I will proceed to describe its construction and operation.

I make a cylinder of iron or other suitable metal, say six inches interior diameter, see drawing A, A, B, B, and to give greater 30 stability I extend the base of the cylinder A, A, in the direction R, and firmly annex the regulator to the steam-boiler or other support by means of screws S, S. The piston C, C, of iron or other suitable metal, is 35 of smaller diameter than the cylinder, leaving a space between it and the cylinder of, say, one-quarter of an inch all around to be occupied by the cylindrical shaped vulcanized india rubber, D, D, D, D. The bottom 40 of the piston C, C, is provided with a projection or flange E, E, which forms a seat upon which the vulcanized india rubber D D' rests. The curved wall of the cylinder A, A, A, A, is provided at a suitable 45 point with an interior projection I, I, which is nearly in contact with the vulcanized india rubber and incloses it between the piston, the cylinder, the flange, E, E, and the projection I, I. The standard or bar K, K, 50 rests upon the piston at its lower end—and passes through the top of the cylinder. The lever L, L, which turns upon the fulcrum M rests upon the upper point of the standard K, K, as is represented at N. The lever 55 is made of iron, but the wearing parts of the lever as well as the fulcrum and the standard K had better be of steel. An adjustable weight O, slides upon the lever. The

lever is connected by means of the rod P, with the crank Q, which turns the damper 60 T in the flue or chimney.

I now proceed to describe the operation of the regulator. By means of the pipe U, at the bottom of the cylinder, connection is made with the steam boiler. In order to 65 prevent the access of steam from the boiler to the vulcanized india rubber, I make a depressed bend in a horizontal part of the pipe U, or an equivalent ∞ shaped bend in a vertical pipe, the effect of which bend as 70 is well known and as is commonly used in other apparatuses, is to cause a deposit of water in the pipe at the bend and thus prevent the contact of steam with the vulcanized india rubber which would be injurious, 75 or to effect the same purpose I connect the pipe U, with the boiler at a point below the level of the water in the boiler. It is evident that, when the weight O is adjusted upon the lever to balance any desired pressure of steam in the boiler, the piston C, C, 80 will rise when the pressure of the steam in the boiler exceeds the desired pressure until it is stopped by the resistance of the vulcanized india rubber, or by the set screw V. A 85 very slight motion of the piston C, C, communicated to the lever L, by the standard K, suffices to turn the crank Q and damper T, so as to diminish the sectional area of the flue or chimney, and thus check the 90 draft and diminish the combustion of fuel and thereby diminish and regulate the generation and pressure of steam in the boiler. The vulcanized india rubber should nearly 95 but not completely fill by its thickness the space between the piston and the cylinder.

I do not claim the regulating of fires and dampers by means of a piston moving in a cylinder, acted upon by the pressure of the steam in the boiler, such apparatus having 100 been used before. Nor do I claim the use of vulcanized india rubber as steam packing of pistons, it having been used for such purpose before.

What I claim as new and my improvement, and desire to secure by Letters Patent, 105 is—

The combination and arrangement of the cylinder A, A, B, B, the piston C, C, and packing D, D, D, substantially as shown 110 and described.

WILLIAM WEBSTER.
